UNITED STATES PATENT OFFICE.

SETH WHEELER, OF CASTLETON, NEW YORK.

PROCESS OR METHOD OF PRODUCING PACKAGES OF INTERFOLDED SHEETS.

No. 821,562.

Specification of Letters Patent.

Patented May 22, 1906.

Application filed June 6, 1905. Serial No. 263,947.

To all whom it may concern:

Be it known that I, SETH WHEELER, a citizen of the United States of America, and a resident of Castleton, in the county of Rensselaer, State of New York, have invented certain new and useful Improvements in a Process or Method of Producing a Package of Interfolded Sheets, of which the following is a specification, reference being had to the accompanying drawings, forming a part thereof.

My invention relates to an improved process of producing a package of interfolded sheets, and particularly to a process of producing a package of one, two, or more superposed sheets folded into books of three leaves with their terminals interfolded.

In carrying out my invention the sheet or sheets are severed from a continuous web or webs and suitably folded and interfolded continuously until the package is finally completed.

The main object of my invention is to produce a package of this description by interfolding the terminals of the folded sheets at the time the folds are made, the sheets themselves being cut from a web, so that the process of forming the completed package is a continuous one from the time the paper leaves the web to the time the completed package is formed.

In carrying out my invention I first take a single sheet or a unit composed of two or more superposed sheets and partially fold same. I then take a second sheet or unit of sheets and insert the forward end of the new sheet into the partially - completed fold. Next I complete the fold of the first sheet, including in this fold the forward end of the second sheet, then fold the new sheet over the terminal of the preceding sheet and partially backward upon itself. I then take another sheet or unit of sheets and insert the forward end of the last-taken sheet into the incomplete terminal fold of the preceding sheet, and so on. The result of the foregoing steps in the order named is a package containing a plurality of books each having three leaves, the terminal leaves of contiguous books being interfolded. Each book contains one, two, or more sheets, as may be desired.

In the drawings herewith, which illustrate the several steps in the process and a package resulting therefrom, Figures 1, 2, 3, 4, 5, and 6 are diagrammatic views illustrating the folding and interfolding of the sheets.

Fig. 7 is a view in perspective of a package of interfolded sheets; and Fig. 8 is a diagrammatic view showing two three-leaved books with their terminals interfolded, each book comprising two superposed sheets.

Referring to the drawings by reference characters, 10 designates a roll of paper constituting a web to form a continuous supply for the sheets.

In Fig. 1 the web is partially unrolled, and a section thereof, constituting a single sheet *a*, is severed from the web at 11.

In Fig. 2 the sheet *a* is shown as completely folded at 12 and partially folded at 13, the folds 12 and 13 being opposite and in opposite directions.

In Fig. 3 a new sheet *b* is shown as severed from the web 10, its forward end being inserted in the incomplete fold 13 of the sheet *a*.

In Fig. 4 the fold 13 of the sheet *a* is shown as completed, the forward end of the sheet *b* being embraced between the body of the sheet *a* and the terminal thereof.

In Fig. 5 the sheet *b* is shown as folded over the terminal end of the sheet *a* at 14 and partially folded backward upon itself, so as to form an incomplete fold at 15.

In Fig. 6 another sheet *c* is shown as having been severed from the web, its forward end being inserted in the incomplete fold 15 of the sheet *b*.

Continuation of the foregoing steps in the order named will result in a package substantially as illustrated in Fig. 7, the package being of any desired thickness in accordance with the number of interfolded units.

For simplicity of illustration and description I have shown and described the sheets *a*, *b*, and *c* as single sheets; but it will be understood that each sheet so shown may be a unit of sheets containing two or more single sheets, if desired.

In Fig. 8 I have shown two interfolded units each containing two superposed sheets.

It is also understood that while I preferably sever the sheets during the process from a continuous web or strip I may, if desired, take the individual sheets or units of sheets from a pile in which they may be contained in a condition already severed.

What I claim is—

1. The herein-described process or method of producing a package of interfolded sheets, which consists in severing a sheet from the web, partially folding the same, severing a new sheet, inserting the forward end of the

new sheet into the partial fold of the preceding sheet, completing the fold of the preceding sheet, folding the new sheet over the end of the preceding sheet and partially backward upon itself, severing another sheet, inserting its forward end into the partial fold of the preceding sheet, and so on.

2. The herein-described process of producing a package of single sheets or units containing two or more superposed sheets, folded into books of three leaves, with their terminals interfolded, which consists in severing a unit from a web, partially folding the same over a new unit, inserting the forward end of

the new unit into the incomplete last fold of the preceding unit, completing the terminal fold of the preceding unit, folding the new unit over the terminal of the preceding unit and partially backward upon itself, severing another unit, inserting its end into the incomplete terminal fold of the preceding unit, and so on.

In witness whereof I have hereunto set my hand this 29th day of May, 1905.

SETH WHEELER.
